FIG. 1

FIG. 2

FIGURE 1 is a plan view of the circular ring toss toy or similar article; the reverse side of the circular ring toss toy or similar article is identical.

FIGURE 2 is a transverse vertical section taken along the line 2—2.

The characteristic feature of my design resides in the combination on a flat ring toy of a central aperture in the configuration of a quatrefoil or four-leaf clover with a single circular aperture between each lobe of said clover-shaped aperture, all as shown.

I claim:

The ornamental design for a circular ring toss toy or similar article, substantially as shown and described.
